ERNEST E. BROWN, OF HOME GARDENS, CALIFORNIA

LIQUID DISPENSING APPARATUS

Application filed August 11, 1930. Serial No. 474,483.

This invention relates to liquid dispensing apparatus and has for an object to provide a rotating remote control for such apparatus, particularly electric motor gasoline pumps, so that the operator may conveniently, with one hand, control both the motor and the nozzle at the same time.

A further object of the invention is to provide an extremely simple and efficient device for controlling the motor at some distance therefrom and comprising essentially a revolving cable extending through or along the length of the hose and operated at the nozzle end of the hose to control an electric switch for starting and stopping the motor.

A still further object of the invention is to provide a remote control for motor driven gasoline pumps which control will be formed of a few simple and durable parts which will be inexpensive to manufacture and will not easily get out of order.

With the above and other objects in view the invention consists in certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification:

Figure 1 is a side elevation with parts broken away showing a motor driven gasoline dispensing pump equipped with my improved rotating remote control,

Fig. 2 is a cross sectional view showing the rotating cable and actuating means therefor as well as showing a mercoid switch controlled by the cable, and

Fig. 3 is a cross sectional view taken on the line 3—3 of Fig. 2.

Referring now to the drawings in which like characters of reference designate similar parts in the various views, a conventional form of gasoline dispensing pump is shown comprising an electric motor pump 10, which is employed to transfer the gasoline from the storage tank through pipes 11 and 12 to a hose 13 which terminates in a delivery

nozzle 14 having therein the usual valve that is opened and closed by a manually operated trigger 15 which extends along the grip 16 of the nozzle.

In the present embodiment of the invention, I preferably employ a mercoid switch 17 of the rotary type. This type switch consists ordinarily of a glass tube containing a small quantity of quicksilver and when the tube is tilted at an angle, the quicksilver runs to the lower end thereof and makes contact between switch points which are connected by wires 18 to the motor of the pump. When tilted in the opposite direction, the quicksilver flows away from the contacts and opens the circuit to stop the motor.

For operating the switch 17, I provide a rotary cable 19 which preferably extends longitudinally through the hose 13, although the cable may be disposed exteriorly along the length of the hose and secured thereto in any preferred manner. One end of the cable is connected to the switch shaft 20 which is journaled in a suitable bearing 21 carried in a housing 22 which may be secured to the casing 23 of the mercoid switch and to a T coupling 23' or like device on the supply pipe 12. The cable rotates the shaft 20 as a unit therewith to tilt the mercoid switch 17 to open or closed positions.

Preferably, the manually operatable means for rotating the cable is mounted in a housing 24. The housing is provided with screw threaded nipples 25 and 26 to engage threaded couplings 27 and 28 on the nozzle and hose respectively.

The end of the rotary cable 19 is equipped with a shaft 29 which is journaled in a bearing 30 disposed within the housing. The shaft is equipped with a pinion 31 which meshes with a bevel gear 32 keyed to a shaft 33, one end of which is journaled in a bearing 34 carried in the housing. The opposite end of the shaft is journaled in a bearing 35 carried by a removable face plate 36 which closes an opening 37 in the housing.

Through the opening 37 the gear and pinion may be properly assembled and thereafter may be conveniently inspected. A gland nut 38 surrounds the shaft exteriorly

of the face plate and prevents leakage. Exterioly of the gland nut a hand lever 39 is secured to the shaft and extends along the grip 16 of the nozzle to overlie the trigger 15 thereof, as best shown in Fig. 1. A spring 39' holds the lever released.

The housing 24, as best shown in Fig. 1, is preferably rectangular in cross section and the face plate 36 is preferably removably secured thereby to screws 40.

The rotary cable 19, as best shown in Fig. 2, is preferably coupled with the pinion shaft 29 by means of a tapered split sleeve 41 which forms an enlargement of the shaft. The cable is held against sliding longitudinally out of the sleeve by means of a lock nut 42 engaged on the threaded exterior of the split sleeve. A similar sleeve 43 and lock nut 44 connects the cable with the switch shaft 20 and unites the cable and switch 17 for rotary movement as a unit.

In operation, when the operator grasps the grip 16 of the nozzle and closes the fingers upon the trigger 15, the palm of the hand will close upon the operating lever 39 whereby both the valve in the nozzle 14 is opened and the rotating cable actuated by means of the meshing gear 32 and pinion 31 to tilt the mercoind switch and close the latter, thereby starting the motor. When the operator releases his grip upon the trigger and operating lever, the spring 39' will throw back the operating lever 39 to rotate the rotary cable in the reverse direction and open the switch to stop the motor.

Having thus described the invention, I claim:

1. A liquid dispensing apparatus comprising a discharge hose, a nozzle thereon, a valve in said nozzle, a rotary cable operatively carried by said hose, means for rotating said cable in one direction when the valve is opened and in the opposite direction when the valve is closed, a rotary switch connected to said cable to open and close an electric circuit, and a motor driven pump controlled by said switch and connected to said hose.

2. A liquid dispensing apparatus comprising a hose, a discharge nozzle thereon, a supply pipe for the hose, a housing connecting the hose with the nozzle, a rotary cable within the hose entering said housing, a manually operatable gear and pinion device in the housing for rotating said cable, a tilting mercoind switch operatively connected to said cable to be tilted thereby to open and close an electric circuit, and an electric motor driven pump connected in circuit with said switch for supplying liquid to said pipe.

3. A liquid dispensing apparatus comprising a hose, a nozzle thereon, a valve in said nozzle, a housing connected to said nozzle and to said hose, a shaft in said housing, an operating lever on the outer end of said shaft extending along said nozzle, a gear and pinion

device in said housing operated by said shaft, a rotary cable disposed within said hose and actuated by said device, a mercoind switch operated by said cable, and an electric motor driven pump in circuit with said switch for supplying liquid to said hose.

4. A liquid dispensing apparatus comprising a hose, a valve controlled nozzle thereon, a rotary cable having one end operatively carried by said nozzle, a manually operated gear and pinion device operatively connected to said nozzle for rotating the cable, a mercoind switch operated by said cable, and an electric motor driven pump controlled by said switch and operatively connected to said hose.

5. A liquid dispensing apparatus comprising a hose, a valve controlled nozzle thereon, a rotary cable carried by said hose and terminating adjacent to said nozzle, a manually operated gear and pinion device carried by said nozzle for actuating said cable, a tilting switch actuated by said cable to open and close an electric circuit, and an electric motor driven pump controlled by said switch and supplying liquid to said hose.

6. The combination with an electric motor driven pump, a hose operatively connected thereto, and a switch for controlling the pump, of a remote rotary control for the switch comprising a rotary cable operatively connected to the switch, and manually operated means disposed near the discharge end of the hose for rotating said cable.

In testimony whereof I affix my signature.

ERNEST E. BROWN. [L.S.]
